JONATHAN HALEY, OF CAMBRIDGE, MASSACHUSETTS.

Letters Patent No. 69,426, dated October 1, 1867.

IMPROVEMENTS IN GLASS-WARE PRESSES.

The Schedule referred to in these Letters Patent and making part of the same.

TO ALL WHOM IT MAY CONCERN:

Be it known that I, JONATHAN HALEY, of Cambridge, in the county of Middlesex, and State of Massachusetts, have invented a new and useful Improvement in Glass-Ware Presses; and I do hereby declare that the following, taken in connection with the drawings which accompany and form part of this specification, is a description of my invention sufficient to enable those skilled in the art to practise it.

In pressing glass-ware it is an object to have the press operate quickly as well as with a power which varies throughout the movement of the parts which operate directly on the mould, the power of movement increasing from the commencement to the end of the pressing motion.

To obtain the object of the first part of my invention, I so construct the press that the bed on which the mould rests moves toward and from the plunger at the same time that the plunger moves toward and from the bed, and it is in this that the first part of my invention consists.

To obtain the object of the second part of my invention, I so connect the movable plunger and the movable bed with cranks that said cranks are substantially in a horizontal position when the bed and plunger are at their greatest distance apart, and so that said cranks shall approach a vertical position when the bed and plunger approach each other; and it is in this arrangement of cranks with reference to the movable bed and plunger that the second part of my invention consists.

The drawing, which illustrates an embodiment of my invention, shows a press in which a section is taken on one side of the centre, exhibiting the parts in elevation beyond the section. The press contains many of the parts now common in glass-ware presses, and the description will be confined as nearly as possible to the matters connected with my invention.

The frame *a* is like the common presses, except that it has a provision therein for reception of a movable bed, *b*, which is guided by projections *c* which fit in ways *d*, which are secured to the frame *a*. On the frame *a* are secured upright pieces *e* in the ordinary manner, in which are formed ways for the guidance of the cross-head *f*, in which may be fitted any desired form of plunger. Attached to this cross-head, and passing through a cross-tie, *g*, uniting the tops of the uprights *e*, is a piston-rod, *h*, which has at its top a cross-bar, *i*, in which there is a provision for adjusting the position of the cross-head and piston-rod, all in a well-known way. In connection with this cross-head *f*, cross-tie *g*, and cross-bar *i*, there is the usual spring-piece *j* and its ordinary attachments, the purpose of which is to rest on the edge of the glass in the mould to prevent it from being withdrawn therefrom when the plunger is being withdrawn. Beneath the frame of the press, and supported therefrom in suitable hangers *k*, is a shaft, *l*, which is cranked at its centre, said crank being marked *m*, and the shaft is also provided at each end with a crank, *n*. Crank *m* is connected to and moves the bed *b* by means of the connecting-rod *o*, and the cranks *n* are connected with the cross-bar *i* by connecting-rods *p*, the arrangement and connection of the cranks and connecting-rods being such that when the bed is down and the cross-head which carries the plunger is up, then the cranks are substantially horizontal, and such also that when the said cranks are vertical then the nearest possible approach of the bed to the cross-head is made.

Now, it will be obvious to mechanicians that for any given angular amount of movement of the lever *q* which turns the cranks and crank-shaft, and with a given power applied to said lever, a movement will be obtained of the bed and plunger in approaching each other that, while it lessens in velocity, increases in power, which is very desirable in glass-ware presses, as at first but little power is required, which power is required to increase from the beginning to the end of the impression given. It will also be obvious that as the bed and plunger move toward each other with equal or nearly equal velocities, but about one-half of the time is consumed in giving an impression that is needed when the bed is stationary and the plunger alone is movable.

In the drawing, the position of the lever shown in red lines is that which it is made to assume in operating the press to move the bed and plunger towards each other, as shown in red lines, the change of position of the cranks from horizontal to vertical being also shown in red lines.

I claim, a press organized substantially as described, so that the bed and plunger have simultaneous movements relative to each other in approaching and receding.

Also, the combination, as arranged, of the cranks, connecting-rods, movable bed, and plunger, carrying cross-head, for the purpose specified.

JONATHAN HALEY.
